UNITED STATES PATENT OFFICE.

WILLIAM G. TROHON, OF DANVERS, MASSACHUSETTS, ASSIGNOR TO KLIP-LOX BOX FASTENER COMPANY, INCORPORATED, OF BEVERLY, MASSACHUSETTS, A CORPORATION OF MASSACHUSETTS.

FASTENING DEVICE FOR BOXES AND THE LIKE.

1,366,611.

Specification of Letters Patent. Patented Jan. 25, 1921.

Application filed October 21, 1919. Serial No. 332,324.

To all whom it may concern:

Be it known that I, WILLIAM G. TROHON, a citizen of the United States, and resident of Danvers, in the county of Essex and 5 State of Massachusetts, have invented an Improvement in Fastening Devices for Boxes and the like, of which the following description, in connection with the accompanying drawings, is a specification, like 10 characters on the drawings representing like parts.

This invention relates to means for securing together two or more pieces of sheet material and is herein illustrated as embodied in a collapsible box having overlapping flaps which serve when fastened together as a closure for the box.

The general object of the present invention is to provide a fastening means which 20 is simple and strong and which may be secured in such a way that the box cannot be casually opened as is desirable when, for instance, the box is to be used as a package for express shipment.

25 Referring now to the accompanying drawings wherein an illustrative embodiment of the invention is shown,

Figure 1 is a perspective of a collapsible box of corrugated board showing the flaps 30 which form the upper cover fastened together;

Fig. 2 is a fragmentary perspective showing one of the fastening devices in position but not completely closed and secured;

35 Fig. 3 is a similar view wherein the fastening device has been completely closed;

Fig. 4 is a perspective view of the keeper element of the fastening, and

Fig. 5 is a plan of the locking member.

40 Referring to Fig. 1, I have there shown a box of well known type wherein closures are formed by two inner flaps 7 folded in from the ends of the box and two outer flaps 9 folded in from the sides and overlying the inner flaps. The closure of such a box may be completed by means of four fastening devices arranged as indicated in Fig. 1.

The form of fastening herein shown may 45 comprise a keeper member conveniently in the form shown in Fig. 4 and consisting of a plate of metal providing a base portion 50 from the body of which is struck up the tongue 13. As indicated in Fig. 2, this

keeper is adapted to be applied to the inner side of the flap 7 with the tongue 13 projecting upwardly through this flap and also through a suitable aperture in the outer flap 9 which conveniently may be reinforced as by an eyelet 15. The tongue 13 is provided with a suitable opening or openings 55 to receive a locking member and I have herein shown two holes 17 which, when the flaps are in their closed position as shown in Figs. 2 and 3, lie substantially in the plane of the outer surface of the overlying 60 flap 9.

To lock the flaps together a suitable locking member 19 is provided coöperating with the keeper member and this may conveniently take the form shown in Fig. 5. As 70 there shown the locking member is formed as a spring key formed from a single length of wire having legs 21 and 23 with rebent ends to provide rounded terminal portions and locking shoulders 25. Conveniently one 75 of the legs as 23 is somewhat longer than the other. The box is locked by inserting the legs of the member 19 through the openings 17 of the tongue 13. The rounded end portions of the key facilitate the introduction of the member as does also the fact that one leg is longer than the other. The locking member is pushed into position until the locking shoulders pass the tongue when the legs spring upwardly and the shoulders 25 80 engage the side of the tongue to prevent withdrawal. In this position the locking member overlies the sides of the opening in the outer flap and bridging the sides of the eyelet securely fastens the box. The locking member lies substantially flat in the plane of the outer surface of the box and by virtue of its construction has an extending bearing thereon.

In preparing packages for shipment by 95 express it is desirable to lock them securely against casual opening. I have herein provided for this by associating with the tongue 13 a displaceable portion which may be manipulated to so position the locking member 100 as to prevent its withdrawal from the tongue 13. Herein the tongue is provided with a projection 27. After the member 19 is inserted as shown in Fig. 2, this projection may, by means of a suitable tool, be 105 bent over to the position shown in Fig. 3,

entering between the legs 21 and 23 of the member 19 and holding them spread in such a manner that they cannot be pressed toward each other to release the locking shoulders 25 from the sides of the opening 17. In the operation of bending in the projection 27 more or less of the body portion proper of the tongue 13 may also be upset, thus reducing the projection of the fastening device beyond the outer face of the box. Conveniently the operation is so carried on as to cause the point of the projection 27 to enter or lie in immediate proximity to the opening in the outer flap 9 to be shielded by 15 the eyelet therein.

The locking member 19 is positioned in the tongue and held against withdrawal and cannot be removed except by breaking or cutting of the parts. The sides of the locking member shield the bent over projection so that a lever cannot be conveniently inserted behind it to pry it upwardly and the point thereof is practically inaccessible and similarly protected by the eyelet.

25 I have herein described one particular form of my invention as herein illustrated embodying a particular form of keeper and of coöperating locking member. Obviously, however, the invention is not limited to the 30 details of construction illustrated and might be embodied in other forms within the scope of the following claims.

Claims:

- 35 1. A securing device for a flap comprising a keeper having an apertured tongue adapted to project past the flap and a locking member receivable in the aperture of said tongue and adapted to overlie the flap, said tongue having a portion displaceable to engage the member thereby to retain it in the tongue.
- 40 2. A securing device for a flap comprising a keeper having an apertured tongue adapted to project past the flap and a locking member insertible in the aperture and having a 45 shoulder to engage the tongue to prevent withdrawal, said tongue having a portion

displaceable to engage the member to hold said shoulder in its engagement.

3. A securing device for a flap comprising a keeper having an apertured tongue 50 adapted to project past the flap, a locking member for insertion in the tongue having legs provided with exterior shoulders, said tongue having a portion displaceable to lie between the legs and hold them spread with 55 the shoulders engaging the tongue.

4. A securing device for a flap comprising an apertured tongue having a bendable projection and a member coöperating with said tongue having legs receivable in the aperture and adapted to be held spread therein by the projection when bent.

5. Means for securing together overlapping sheets comprising a keeper secured to one sheet and having an apertured tongue, the other sheet having an opening to receive said tongue to bring the aperture in the plane of the outer surface of the sheet and a member insertible in the aperture and having a locking shoulder to prevent its withdrawal, said tongue having a portion bendable to engage said member to hold the shoulder engaged and in such position extending to the margin of the opening to be shielded thereby.

6. Means for securing together overlapping sheets comprising a keeper secured to one sheet and having an apertured tongue, the other sheet having an opening to receive said tongue to bring the aperture in the 70 plane of the outer surface of the sheet and a locking member for insertion in the tongue having legs provided with exterior shoulders, said tongue having a portion bendable to lie between the legs and hold them spread 75 with the shoulders engaging said tongue and in such position extending to the margin of the opening to be shielded thereby.

In testimony whereof I have signed my name to this specification.

WILLIAM G. TROHON.
